UNITED STATES PATENT OFFICE.

EDGAR WILSON HEISEY, OF NEWARK, OHIO, ASSIGNOR TO A. H. HEISEY & COMPANY,
OF NEWARK, OHIO, A COPARTNERSHIP.

DESIGN FOR A GOBLET.

Application filed February 21, 1924. Serial No. 8,694. Term of patent 14 years.

To all whom it may concern:

Be it known that I, EDGAR WILSON HEISEY, a citizen of the United States, residing in Newark, State of Ohio, have invented a new, original, and ornamental Design for a Goblet, of which the following is a specification, reference being had to the accompanying drawing, forming a part thereof.

The figure is a perspective view of a goblet to which my design is applied.

I claim:

The ornamental design for a goblet as shown.

EDGAR WILSON HEISEY.
